[57] CLAIM

The ornamental design for a stein shaped building, as shown and described.

DESCRIPTION

FIG. 1 is a front elevational view thereof;
FIG. 2 is a left side elevational view with the right side being a mirror image thereof;
FIG. 3 is a rear view thereof; and,
FIG. 4 is a top view thereof.
The stone patterns are continuous throughout the sections to which they have been applied.
The undisclosed bottom is plain and unornamented.

FIG. 2

FIG. 1

FIG. 4

FIG. 3
